FIG. 1 is a perspective view of a desk showing my new design;

FIG. 2 is a side elevation view thereof;

FIG. 3 is a top plan view thereof;

FIG. 4 is a front elevation view thereof;

FIG. 5 is a rear elevation view thereof;

FIG. 6 is a side elevation view of another form of spline jointed desk assembly having a single pedestal showing my new design;

FIG. 7 is a top plan view of the design of FIG. 6;

FIG. 8 is a front elevation view of the design of FIG. 6;

FIG. 9 is a rear elevation view of the design of FIG. 6;

FIG. 10 is a side elevation of another form of a desk having a double pedestal showing my new design;

FIG. 11 is a top plan view of the design of FIG. 10;

FIG. 12 is a front elevation view of the design of FIG. 10;

FIG. 13 is a rear elevation view of the design of FIG. 10; and

FIG. 14 is an enlarged elevation view of the joint shown in FIG. 5.

I claim:

The ornamental design for a desk, as shown and described.
